US0D1043234S

(12) **United States Design Patent** (10) Patent No.: **US D1,043,234 S**
(45) Date of Patent: ** Sep. 24, 2024

(54) **PRESSURE COOKER LID**

(71) Applicant: **Instant Brands Holdings Inc.**,
Downers Grove, IL (US)
(72) Inventor: **Jason LePinske**, Schaumburg, IL (US)
(73) Assignee: **IB APPLIANCES US HOLDINGS LLC**, Downers Grove, IL (US)

(**) Term: **15 Years**

(21) Appl. No.: **29/845,097**

(22) Filed: **Jul. 5, 2022**

(51) LOC (14) Cl. **31-00**

(52) U.S. Cl.

USPC **D7/391; D7/402; D7/358**

(57) **CLAIM**

The ornamental design for a pressure cooker lid, as shown and described.

DESCRIPTION

FIG. 1 is a top front left perspective view of a pressure cooker lid showing the new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines show portions of the pressure cooker lid that form no part of the claimed design.

1 Claim, 5 Drawing Sheets
